UNITED STATES PATENT OFFICE

ARNOLD H. TOLD, OF CHICAGO, ILLINOIS

ADJUSTABLE RAIL BRACE

Application filed October 21, 1931. Serial No. 570,094.

The present invention relates to rail braces and seeks to provide an improved effective form of adjustable rail brace. The invention consists in the features of improvement 5 hereinafter set forth, illustrated in the preferred forms in the accompanying drawings and more particularly pointed out in the appended claims.

In the drawings:—

Fig. 1 is a perspective view of the improved 10 adjustable rail brace applied to a rail,

Fig. 2 is a cross section,

Fig. 3 is an end view of a modified form,

Fig. 4 is a plan view of the form shown in 15 Fig. 3.

Fig. 5 is a plan view of another modified form.

Fig. 6 is an end view of the form shown in Fig. 5.

Fig. 7 is a plan view of still another form,

Fig. 8 is an end view of the form shown in Fig. 7, and

Fig. 9 is a side elevation of a modification of the form shown in Figs. 7 and 8.

The improved rail brace is applicable to main rails and also to switch and guard rails. It includes a tie plate 10 which is adapted to extend beneath the rail A to which the brace is applied. An angular bracket 11 is secured to the tie plate 10 and comprises horizontal and vertical portions 12 and 13 and an integral, inclined brace rib or strut 14.

The brace rib 14 is preferably hollowed out as indicated in Figs. 2 and 4, and recesses are preferably formed in the inside bottom corner of the bracket on opposite sides of the brace rib as indicated in dotted lines in Fig. 4 to further lighten the weight of the bracket without objectionably reducing its strength.

The bracket is rigidly secured to the tie plate by rivets 15 as shown, which extend through the horizontal or base portion 12 of the bracket. The inner vertical portion of the bracket is adapted to extend over the base flange b of the rail but so as to provide considerable clearance between the bracket and the rail base. In the form shown in Figs. 1 and 2, the base portion 12 of the bracket is of considerable length and is secured to the tie plate 10 by the rivets 15. In the form shown

in Figs. 3 and 4, the base portion 12 of the bracket is shorter and abuts against a toe block 16 which is also riveted to the tie plate, but which, if desired, may be formed from a turned-up end of the tie plate.

The inner face of the upright portion 13 of the bracket is horizontally inclined, that is to say, is at an angle to the longitudinal axis of the rail and is arranged to engage the outer face of a wedge 17 which is driven into position between the bracket and the rail, and which can be adjusted from time to time as may be necessary by the wear of the different track structures to which the brace is applied.

The wedge is preferably cored out on its inner face to provide a recess 18 leaving horizontally extending bearing portions 19 and 20 at its upper and lower edges which are arranged to engage portions of the head and base of the rail adjacent the web, and which are preferably shaped to fit and have load bearing engagement with the head and base fillets of the rail.

The horizontally inclined contacting faces of the bracket and wedge are vertically disposed so that the wedge, which as stated engages portions of the head and base of the rail, is free to rise and fall with the rail. This is also permitted by the clearance between the bracket and the rail base, and with this arrangement the wave motion of the rail effected by traffic will not place any strain on the bracket and tie plate nor on the means for securing these parts together. In the preferred form, the wedge is provided on its outer face with a horizontally extending rib 21 which extends through a groove 22 in the inner face of the bracket, but clearance is provided between the rib and the walls of the groove to permit the vertical movement of the wedge with the rail and relative to the bracket.

Means are provided for securing the wedge in its adjusted position, and this is highly important in order to prevent the backing up of the wedge and the spreading of the rail. For this purpose, one of the bracket and wedge parts is provided with ratchet teeth and the other with a one-way yielding, spring-held dog for engaging the ratchet teeth to thereby automatically secure the wedge in adjusted position. In the form shown in Figs. 1 and 2,

ratchet teeth 23 are formed upon the upper face of the rib 21, and a pair of dogs 24 arranged within the recess 22 of the bracket above the teeth, are mounted upon a pivot pin 25. Spring fingers 26 formed from a plate and secured to the bracket by a rivet 27 engage the tail portions 28 of the dogs and force the beveled teeth on their outer ends into engagement with the ratchet teeth 23. The locking arrangement shown in Figs. 3 and 4 is similar to that shown in Figs. 1 and 2 except that the ratchet teeth 23 are formed upon the vertical face of the wedge 17 instead of upon the upper face of the rib 21. As the wedge is driven to position or adjusted to take up wear, the dogs will yield to permit the forward movement of the wedge, but since back pressure on the wedge will force the tails of the dogs against the bracket, the dogs serve to automatically secure the wedge in the position to which it is adjusted and prevent it from backing up. Either the ratchet teeth or the pointed end portions or teeth 29 of the dogs, are staggered so that the teeth may be of sufficient size and yet permit slight adjustments of the wedge. Preferably, the outer ends of the dogs 30 are extended beyond their teeth 29 so that they can be lifted when it is desired to remove the wedge.

In the form illustrated in Figs. 5 and 6, the wedge is provided with a plurality of longitudinally spaced grooves 30 and the bracket is provided with a pair of grooves 31 and 32. All of the grooves just mentioned are preferably of semi-circular cross-section and the grooves 31 and 32 in the bracket 11 are preferably spaced approximately $1\frac{1}{2}$ times the spacing of the grooves 30 in the wedge 17. By this arrangement, it will be observed that the grooves 30 are each engageable with either one of the grooves 31 and 32 upon longitudinal adjustments of the wedge equal to $\frac{1}{2}$ the center to center spacing of the grooves 30. A pin 33 may be inserted in the registering grooves of the wedge and bracket as shown to lock the parts in adjusted position. If desired, the pin 33 may have its upper end bent over as indicated at 34 to facilitate removal thereof in the event that it becomes necessary to adjust the brace.

In the form indicated in Figs. 7 and 8, the wedge 17 is provided with a rib 34 which fits in a groove 35 formed in the bracket part 11, the groove 35 being of such vertical dimension that the rib may move vertically therein as an incident to the wave motion of the rail A. For locking the wedge in adjusted position, the rib 34 may be split from the wedge proper a suitable distance, for example approximately $\frac{1}{2}$ the length of the wedge, and the forward end of the rib may then be sprung outwardly as indicated at 36 to prevent rearward movement of the wedge relative to the bracket.

In the form illustrated in Fig. 9, the rib

34 is split from the wedge substantially as above described in connection with Figs. 7 and 8 and in addition, the rib is split horizontally for approximately $\frac{1}{2}$ the length of the wedge as indicated at 37. For locking the wedge against rearward movement, the split forward end of the rib may then be spread in a vertical direction as indicated at 38. This last described arrangement may have some tendency to resist vertical movement of the wedge and rail relative to the bracket but the resiliency of the metal rib is sufficient to permit such movement.

The improved locking means serves to effectively prevent the wedge from backing up and at the same time avoids the necessity of using bolts or cotter pins or other such separate parts which are apt to become loose and ineffective or be improperly applied so as to create a dangerous condition.

The improved brace can readily be applied to rails of different sizes and shapes without changing the size and shape of the bracket, it being only necessary to provide a suitable wedge to properly fit and support the rail. If desired, the upper edge of the wedge can be extended to give additional support to the head of a standard rail, or if desired, it can be extended and shaped to fit against the upper portion of a so-called "head free" rail A' as shown in Fig. 3.

Other changes may be made in the details set forth without departure from the scope of the invention as defined in the appended claims.

I claim as my invention:

1. A rail brace comprising a tie-plate, a bracket secured thereto, a wedge adapted to be driven between the bracket and the rail and engage portions of the rail base and head, and means for securing the wedge in adjusted position arranged to permit vertical movement thereof relative to the bracket as an incident to the normal wave motion of the rail, substantially as described.

2. A rail brace comprising a tie-plate, a bracket secured thereto and arranged to extend over and out of contact with the rail base, a wedge adapted to be driven between the bracket and the rail and engage the head and base fillets of the rail, the bracket and wedge having vertical, horizontally inclined engaging faces, and means for securing the wedge in adjusted position arranged to permit the vertical movement of the wedge with the rail, substantially as described.

3. A rail brace comprising a tie-plate, a bracket secured thereto, a wedge adapted to be driven between the bracket and the rail and have a load bearing engagement with the head and base fillets of the rail, the bracket having a horizontal groove and the wedge being provided with a rib extending through said groove with clearance to per-

mit the vertical movement of the wedge with the rail, and means cooperating with the rib to secure the wedge in adjusted position, substantially as described.

5. A rail brace comprising a tie-plate, a bracket secured thereto and arranged to extend over and out of contact with the rail base, a wedge adapted to be driven between the bracket and the rail and engage the head and base fillets of the rail, the bracket and wedge having vertical, horizontally inclined engaging faces, and being provided respectively with a horizontal groove and a rib extending through the groove with clearance to permit vertical movement of the wedge with the rail, and means cooperating with the rib for securing the wedge in adjusted position, substantially as described.

6. A rail brace comprising a tie-plate, a bracket secured thereto, a wedge adapted to be driven between the bracket and the rail and engage portions of the rail base and head, one of said brackets and wedge parts having ratchet teeth formed thereon, and a spring held dog on the other of said parts for engaging the ratchet teeth to automatically secure the wedge in adjusted position, substantially as described.

7. A rail brace comprising a tie-plate, a bracket secured thereto, a wedge adapted to be driven between the bracket and the rail and have a load bearing engagement with the head and base fillets of the rail, the bracket having a horizontal groove and the wedge having a rib extending through said groove and being provided with ratchet teeth, and a one-way yielding, spring held dog mounted on the bracket and arranged to engage the teeth to secure the wedge in adjusted position.

8. A rail brace comprising a tie plate, a bracket secured thereto, a wedge adapted to be driven between the bracket and the rail and having a load bearing engagement with the head and base fillets of the rail, the bracket having a horizontal groove and the wedge being provided with a rib extending through said groove with clearance to permit the vertical movement of the wedge with the rail relative to said bracket and means secured to the bracket and engaging a portion of said wedge for locking the wedge in adjusted position.

9. A rail brace comprising a tie plate, a bracket secured thereto, and a wedge adapted to be driven between the bracket and the rail, the bracket having a horizontal groove and the wedge being provided with a rib extending through said groove with clearance to permit vertical movement of the wedge with the rail relative to the bracket, said rib being provided with a longitudinally extending slit extending only a part of the length of the rib whereby the rib is adapted to be displaced from its normal po-

sition to lock the wedge in adjusted position.

10. A rail brace comprising a tie plate, a bracket secured to said tie plate, a wedge adapted to be driven between the bracket and a rail seated on said tie plate, said wedge having a series of grooves in its outer face and the inner face of said wedge having a groove adapted to register with one of the grooves in said wedge, and a pin disposed in the registering grooves for locking said wedge in adjusted position, substantially as described.
